FURNACE GRATE

John Phillips Badenhausen, Meadowbrook, Pa.

Application January 25, 1949, Serial No. 72,576

6 Claims. (Cl. 126—174)

1

My invention relates to furnace grates and more particularly to an improved reciprocatory grate which is adapted for continuous or intermittent movement, as desired.

It is the principal object of the present invention to provide a furnace grate with improved provisions for cutting or slicing the lower portion of the ash bed for the removal of ash and clinkers for discharge.

It is a further object of the present invention to provide a furnace grate of the reciprocating type in which the entire grate surface is active and effective, in which adequate provision is made for preventing the cascading of coal through the openings in the grate surface, and in which adequate provision is made for delivery of air through the grate.

It is a further object of the present invention to provide a furnace grate capable of operation with a relatively high pressure of air for the penetration of the bed supported thereon.

It is a further object of the present invention to provide a furnace grate which is particularly suitable for use with producer gas furnaces in which a relatively thick bed of fuel is employed and in which combustible gas is generated for subsequent completion of combustion in the same furnace.

It is a further object of the present invention to provide a furnace grate of great strength and in which reciprocatory movement may be readily effected for ash and clinker removal.

Other objects and advantageous features of the invention will be apparent from the specification and claims.

The nature and characteristic features of the invention will be more readily understood from the following description, taken in connection with the accompanying drawings forming part hereof, in which:

Figure 1 is a fragmentary longitudinal sectional view through a furnace having mounted therein a furnace grate in accordance with the present invention, and taken approximately on the line 1—1 of Fig. 2; and

Fig. 2 is a transverse sectional view taken approximately on the line 2—2 of Fig. 1.

It should, of course, be understood that the description and drawings herein are illustrative merely, and that various modifications and changes may be made in the structure disclosed without departing from the spirit of the invention.

Like numerals refer to like parts throughout the several views.

2

Referring now more particularly to the drawings in which a preferred embodiment of the invention is illustrated, a furnace preferably of the producer gas type is illustrated at 10 and includes pairs of parallel side walls 11 and 12 and parallel front and rear walls 13 and 14 extending upwardly from a floor 15. A longitudinal central supporting wall 16, extending upwardly from the floor 15, is provided for purposes to be explained.

10 The side walls 11 and 12 may be provided, spaced upwardly from the lower part thereof, with side wall headers 17 to which suitable steam generating tubes 18, lining the upper portions of the side walls 11 and 12, are connected. The 15 front wall 13 may be provided with a front wall header 19 to which steam generating tubes 20, extending upwardly in the front wall 13, may be connected. The rear wall 14 may also be provided with steam generating tubes 21 mounted therein and, if desired, downcomer tubes 22 may also be provided.

The specific arrangement of the headers 17 and 19, and the steam generating tubes connected thereto forms no part of the present invention 25 and a further detailed description is not believed necessary.

The front wall 13 is provided with a recess or chamber 23 of a size to permit of a portion of the grate passing therewith as hereinafter explained, and the rear wall 14 is provided with a similar recess or chamber 24 for the same purpose.

30 The foregoing furnace is adapted to have mounted therein a reciprocating grate which will now be more particularly described. Spaced upwardly from the bottom wall or floor 15, a plurality of horizontal side beams 25 and a central horizontal beam 26 are provided, the beams 25 and 26 being secured in position for supporting the 35 furnace grate. The central beam 26 is supported by the central wall 16.

The furnace grate includes an upper grate face composed of transverse bars, hereinafter more fully described, and parallel longitudinally extending supporting beams. The supporting 40 beams preferably comprise horizontal side beams 27 and a central beam 28. The side beams 27 and the central beam 28 at their lower portions are provided with sockets 29 for the reception of rollers 30 in rolling engagement with the upper flanges of the beams 25 and 26 for permitting longitudinal movement of the furnace grate.

Intermediate the ends of the beams 27 and 28, vertically extending abutment blocks 31 are provided on the web portions of the beams 27 and 28

for engagement by eccentrics 32 mounted on and rotatable with a transverse shaft 33. The shaft 33 is journalled at 34 in the side wall 11, and at 35 in the side wall 12, and is provided at its outer end with a seal 36 for preventing gas or air leakage. A driving connection 37 is provided on the outer end of the shaft 33 for operation by any suitable driving means (not shown) for effecting reciprocating movement of the grate upon rotation of the shaft 33.

The flange portions of the beams 27 and 28 preferably have mounted thereon, on the upper faces thereof, a plurality of transversely extending grate bar members 40, 41 and 42. The grate bar members 40, 41 and 42 are preferably substantially Z-shaped in vertical cross section and a plurality of different heights of bar members are preferably employed.

As particularly illustrated, bar members 40, 41 and 42 of three different heights are preferably employed in descending or ascending groups. The Z-shaped bars 40, 41 and 42 preferably respectively include lower horizontally disposed clamping flanges or strips 43, 44 and 45 of a width and arrangement to provide spaced openings 46, 47 and 48 along the flanges of the beams.

The Z-shaped bars preferably also include vertically extending webs 49, 50 and 51 of a height which determines the height of the respective bars 40, 41 and 42 and are also provided with upper horizontally disposed supporting and cutting flanges or strips 52, 53 and 54 respectively. The flanges 52, 53 and 54 are offset longitudinally with respect to the lower flanges 43, 44 and 45 and the vertical webs 49, 50 and 51, and thus are arranged in overlapping relationship with respect to the openings 46, 47 and 48.

Each of the Z-shaped bars 40, 41 and 42 is preferably provided with a plurality of transversely spaced web plates 55 longitudinally disposed, and with the web plates 55 of the respective bars in alignment. The web plates serve to stiffen the bars and also serve to cut the ash and clinker longitudinally as hereinafter explained.

It will be noted that by the use of bars 40, 41 and 42 of different heights as illustrated, an uneven supporting surface is provided at the lower part of the bed thus facilitating the cutting of the ash and the clinker in the bed upon reciprocatory movement of the grate.

At the rear end of the beams 27 and 28, a rear closure bar 56 is provided, preferably comprising an angle with a horizontal leg 57 and a vertical leg 58, the legs being connected by longitudinally disposed transversely spaced webs 59 similar to the plates 55. At the front end of the beams 27 and 28, a front closure plate 60 is provided, preferably consisting of an angle with unequal legs, a horizontally disposed short leg 61 and a vertically disposed long leg 62 being provided. The legs 61 and 62 have extending therebetween, at transversely spaced locations, webs 63 similar to the plates 55.

The bed in the furnace 10, and supported by the grate, may comprise in the usual manner, a lower layer of ash and clinker, an intermediate layer of burning material and an upper layer of fresh fuel. The fuel employed may be of any desired character such as bituminous coal, coke, coke breeze or any other preferred fuel. The furnace is preferably operated as a producer gas furnace, that is, a furnace in which the carbonaceous material in the fuel bed is oxidized

to CO with completion of combustion effected above the fuel bed with additional air supplied to the combustible gas released in the fuel bed.

The grate is preferably continuously reciprocated with a velocity of travel of the order of two inches per minute for a furnace width of eight feet and a furnace depth of twelve feet. Upon rotation of the shaft 33, the eccentrics 32 by their engagement with the abutment blocks 31 carried by the beams 27 and 28, actuate the grate. Upon forward movement of the grate, the upper web plates 55 are effective for cutting the lower portion of the bed with longitudinal cuts and upon rearward movement of the grate, the flanges 52 and 53 and 54 cut the bed horizontally and at different levels.

Upon rearward movement of the grate, the material cut by flanges 52, 53 and 54 is directed downwardly in the spaces between the respective bar members and is also further cut by the lower web plates 55 and directed to the openings 46, 47 and 48 for discharge into the plenum chamber therebelow.

Air supplied to the plenum chamber in any desired manner moves upwardly through the material supported by the grate for combustion. The rate of movement of the grate, of course, may be varied as desired in accordance with the particular fuel supplied to the furnace, the rate of combustion of the fuel, and the rate of ash production. The undesired escape of fine particulate material is prevented by reason of the location of the openings 46, 47 and 48 in offset relationship to the flanges 52, 53 and 54.

I claim:

1. In a reciprocatory furnace grate adapted to be interposed between a fire bed and an ash pit, a plurality of parallel supporting beams, fixed supporting members for said beams, a plurality of bar members secured to and transversely disposed with respect to said beams, said bar members comprising spaced upper strip portions and spaced lower strip portions connected thereto, said upper strip portions having upper fire bed supporting faces and edge portions for engagement with the fire bed for separating portions thereof, the openings between said upper strip portions being offset longitudinally of said beams with respect to the openings between said lower strip portions to prevent free downward movement of material from the fire bed to the ash pit, and members engageable with said beams for reciprocating said beams and the bars secured thereto with respect to said supporting members.

2. In a reciprocatory furnace grate adapted to be interposed between a fire bed and an ash pit, a plurality of parallel supporting beams, fixed supporting members for said beams, a plurality of bar members secured to and transversely disposed with respect to said beams, said bar members comprising upper horizontal transversely extending longitudinally spaced strip portions and lower horizontal transversely extending longitudinally spaced strip portions connected to and offset with respect to said upper strip portions, said upper strip portions having upper fire bed supporting faces and edge portions for engagement with the fire bed for separating portions thereof, the openings between said upper strip portions being offset longitudinally of said beams with respect to the openings between said lower portions to prevent free downward movement of material from the fire bed to the ash pit, and members engageable with said beams for

reciprocating said beams and the bars secured thereto with respect to said supporting members.

3. In a reciprocatory furnace grate adapted to be interposed between a fire bed and an ash pit, a plurality of parallel supporting beams, fixed supporting members for said beams, a plurality of bar members secured to and transversely disposed with respect to said beams, said bar members comprising upper longitudinally spaced strip portions respectively disposed at a plurality of different levels and lower longitudinally spaced strip portions connected thereto, said upper strip portions having upper fire bed supporting faces and edge portions for engagement with the fire bed for separating portions thereof, the openings between said upper strip portions being offset longitudinally of said beams with respect to the openings between said lower portions to prevent free downward movement of material from the fire bed to the ash pit, and members engageable with said beams for reciprocating said beams and the bars secured thereto with respect to said supporting members.

4. In a reciprocatory furnace grate adapted to be interposed between a fire bed and an ash pit, a plurality of parallel supporting beams, fixed supporting members for said beams, a plurality of bar members transversely disposed in engagement with and secured to said beams, said bar members comprising upper horizontal transversely extending longitudinally spaced strip portions respectively disposed at a plurality of different levels, lower horizontal transversely extending longitudinally spaced strip portions, vertically extending portions connecting said upper and lower portions, said upper strip portions having upper fire bed supporting faces and edge portions for engagement with the fire bed for separating portions thereof, the openings between said upper strip portions being offset longitudinally of said beams with respect to the openings between said lower portions to prevent free downward movement of material from the fire bed to the ash pit and members engageable with said beams for reciprocating said beams and the bars secured thereto with respect to said supporting members.

5. In a reciprocatory furnace grate adapted to be interposed between a fire bed and an ash pit, a plurality of parallel supporting beams, fixed supporting members for said beams, a plurality of bar members transversely disposed with respect to said beams and secured thereto,

said bar members comprising spaced upper strip portions and spaced lower strip portions, said upper strip portions having upper fire bed supporting faces and edge portions for engagement with the fire bed for separating portions thereof, the openings between said upper strip portions being offset with respect to the openings between said lower portions to prevent free downward movement of material from the fire bed to the ash pit, said bar members having aligned vertically disposed longitudinally extending web portions between said strip portions for vertical longitudinal cutting of furnace bed material, and members engageable with said beams for reciprocating said beams and the bars secured thereto with respect to said supporting members.

6. In a reciprocatory furnace grate adapted to be interposed between a fire bed and an ash pit, a plurality of parallel supporting beams, fixed supporting members for said beams, a plurality of bar members transversely disposed with respect to said beams and secured thereto, said bar members comprising upper spaced strip portions and lower spaced strip portions, said upper strip portions having upper fire bed supporting faces and edge portions for engagement with the fire bed for separating portions thereof, the openings between said upper strip portions being offset with respect to the openings between said lower portions to prevent free downward movement of material from the fire bed to the ash pit, roller members interposed between said beams and said supporting members for supporting said beams for longitudinal reciprocatory movement, and members engageable with said beams for reciprocating said beams and said bars.
